TRACK CIRCUIT APPARATUS

Howard A. Thompson, Edgewood, Pa., assignor to
The Union Switch & Signal Company, Swiss-
vale, Pa., a corporation of Pennsylvania

Application September 30, 1939, Serial No. 297,389

7 Claims. (Cl. 246—34)

My invention relates to track circuit apparatus and more specifically to apparatus of this character which provides protection against false energization of a track relay due to failure of the insulated rail joints which serve to insulate adjoining track circuits.

One object of my invention is to incorporate the protective features into the rail joints themselves by passing current through the rail joints in a novel manner. Another object is to eliminate the necessity for using polarized or two-position track relays and staggering the polarity of adjoining track circuits to avoid false relay operation. A further object is to provide apparatus which will be simple, safe, and reliable in its operation. Other objects and advantages will become clear as the description progresses.

I shall describe several forms of apparatus embodying my invention and shall then point out the novel features thereof in claims.

In the accompanying drawing, Fig. 1 is a diagrammatic view showing one form of apparatus embodying my invention. Figs. 2, 3 and 4 are diagrammatic views showing modified forms of the apparatus shown in Fig. 1, and also embodying my invention.

Similar reference characters refer to similar parts in each of the several views.

In railway signaling track circuits, provision must be made against false energization of the track relays due to leakage of current from adjoining track circuits over rail joints in which the insulation has been broken down. In general, this false energization can be prevented by using polarized or two-element track relays and staggering the polarity in adjoining track circuits so that the leakage current will cause a reversal or deenergization of the track relay. In alternating current track circuits, the use of two-element track relays sometimes presents a problem due to the fact that when the transmission line is sectionalized, one element of the track relay at the sectionalizing location may receive current from one source of supply while the other element receives its energy from a different source, thus rendering the relay inoperative. Accordingly, difficulties are encountered with two-element alternating current relays where sectionalizing must be employed.

The apparatus embodying my invention does not require a two-element track relay and is capable of providing broken-down insulated rail joint protection in any alternating current track circuit, whether on a steam road or in electric propulsion territory. The insulated rail joints

which I employ may be of the usual type except that the method of making the track circuit connections is changed. In the event that the insulation breaks down, it is not only impossible for track circuit energy to feed around the defective joint into the adjoining track circuit, but the failure will also be indicated by the deenergization of the track relay in the track circuit wherein the failure has occurred.

10 This protection is obtained by arranging the electrical connections to the insulated joint in such a manner that if the insulation between one rail and the angle bars which supports the rail is broken down, one half of the impedance bond 15 which is connected to that rail will be short-circuited, thereby effectively short-circuiting the track circuit. It will be apparent, therefore, that my invention permits the use of single element alternating current track relays (or single element 20 direct current track relays energized from a transformer and rectifier combination) thus eliminating the transmission line sectionalizing problem without sacrificing broken-down rail joint protection.

25 Referring now to Fig. 1 of the drawing, the reference characters 1 and 1a designate the two rails of a stretch of track divided by the insulated rail joints A and B to form two track circuit sections C—D and D—E. These rail joints are 30 shown in detail at the location D but are shown diagrammatically at the locations C and E in order to simplify the disclosure. It will be understood, however, that the rail joints at locations C and E are constructed in the same manner as those shown at location D. Each track relay TR is energized from its associated track transformer T over the rails and a suitable current limiting reactor X, in the usual manner. Each track transformer is energized from a suitable 35 source of alternating current having the terminals BX—CX. The impedance bonds 1B are connected across the rails at the two ends of each track circuit for the usual purpose of permitting the flow of propulsion current over the two rails 40 in parallel, without interfering with the operation of the alternating current track circuits.

I shall now describe the manner in which the 45 electrical connections are made at the insulated rail joints to provide protection in the event that the insulation breaks down. Looking at the rail joints A and B at location D, the reference characters 2, 2a designate the angle bars which serve to clamp the two rail ends together through the rail joint insulation 3, 3a, and the reference character 4 designates the insulating end post be-

tween the two rail ends. For simplicity, I have not shown the clamping bolts in the diagram but it will be understood that the usual arrangement of bolts which are insulated from the angle bars is used.

Propulsion current flowing in rails 1 and 1a of section C—D will flow through the two halves of the impedance bond IB to its mid-point. From this mid-point, the path of the current may be traced through wire 5, angle bar 2a, wire 6, angle bar 2, wire 7, angle bar 2a, wire 8, angle bar 2, and wire 9, to the mid-tap of the impedance bond IB and the two rails of section D—E. Should any of the connections in this path become broken, the propulsion current will be interrupted (in the case of a single track road where cross-bonding is not present to provide an alternate path for the propulsion current) and the train will fail to receive propulsion energy as it passes from one to the other section so that this condition will be readily detected. On a multiple track road, visual inspection may be used. If, on the other hand, the insulation 3 or 3a between the upper rail 1 and the angle bars 2 and 2a should fail, then the upper half of the impedance bond IB immediately to the left of the faulty rail joint will become short-circuited, as will be obvious from the drawing, so that the track circuit voltage between the rails 1 and 1a will be reduced to practically zero whereupon the track relay TR at location C will release. Likewise, if the insulation 3 or 3a between the lower rail 1a and the angle bars 2 and 2a should fail, the lower half of the impedance bond IB will be short-circuited, with the same result.

If the insulation between the rail 1 of section D—E and either of the angle bars 2 and 2a should fail, a short-circuit will be placed on the upper half of the impedance bond IB immediately to the right of the rail joint so that the track circuit voltage in section D—E will be reduced to practically zero and the associated track relay TR will accordingly release. Similarly, a failure of the insulation between the rail 1a of section D—E and either of the angle bars will cause a short-circuit to be placed on the lower half of the bond IB, causing relay TR to release.

It will be apparent from the foregoing that the apparatus provides effective protection in a simple and direct manner against any failure of an insulated rail joint in an alternating current track circuit such as might endanger traffic passing through the section. It will also be noted that the ordinary type of insulated rail joint may be used in this apparatus, the chief difference being in the manner of making connections to the various parts of the rail joint. In the event that the rail joint breaks down, it is not only impossible for track circuit energy to be fed around the rail joint into the adjoining track circuit, which precaution is ordinarily considered sufficient from the standpoint of protection to traffic, but the fault will also be indicated by a release of the track relay in the associated track circuit.

The nature of the protection which the apparatus provides is such that it is not essential to use two-element or polarized track relays for the purpose of obtaining the necessary breakdown rail joint protection because the failure will be detected by a single-element type of track relay. Accordingly, the transmission line sectionizing problem no longer offers any difficulty.

In the case of a propulsion road, the impedance bonds IB will already be present in the track circuit so that nothing more than a reconnection

of the insulated rail joints will be required. In steam road territory, however, it will ordinarily be necessary to provide auxiliary impedance bonds but in this case, these may be nothing more than small reactor coils. On account of the absence of propulsion current, the connections to the angle bars and to the auxiliary impedance bonds will not be checked automatically in the latter case. However, this condition is not very serious because the nature of these connections is such that they can readily be checked by visual inspection as often as conditions require. If an automatic check is desired, then the apparatus of Fig. 2 can be used to provide the required indication.

Referring now to Fig. 2, the insulated rail joints A and B are shown diagrammatically in this figure, for simplicity, but it will be understood that the construction of these joints and the electrical connections thereto are identical with those previously described for the rail joints A and B of Fig. 1. In order to check the continuity of the circuit through the rail joints, I have provided a checking transformer CT which furnishes a small checking current sufficient to maintain the checking relay CR energized. The track transformer T1 and the track relay TR1 each have a mid-tap in the track-connected winding through which the checking current is caused to flow. This current will not cause any appreciable change in the flux condition of either device since the direction of the checking current is opposite in the two halves of the winding of each device. The current limiting reactor X1 is preferably connected in series with the input rather than the output winding of the transformer T1 in order not to cause too much unbalance in the checking current in the two rail paths which this current takes.

As will be obvious from the drawing, the checking current from the output winding of the transformer CT flows through the winding of relay CR and divides in the winding of relay TR1 so that one portion flows over rail 1 and the other portion flows over rail 1a. The checking current then unites in the right-hand bond IB1 and flows over the rail joint connections 9, 10 and 11 whereupon it again divides as it flows through the left-hand impedance bond IB1 and over the rails 1 and 1a, to unite again as it leaves the mid-point of the output winding of transformer T1 and returns to the checking transformer CT.

Should any connection become broken in the checking circuit traced above, relay CR will release, opening its front contact 12—13 and closing its back contact 12—14 to provide the necessary indication of the fault, or to control any other suitable protective apparatus. Also, should the insulation fail in either of the insulated rail joints A or B, then one-half of the associated impedance bond IB1 will become short-circuited, as in Fig. 1, to cause the track relay TR1 to release. The apparatus of Fig. 2 therefore provides the same type of protection as the apparatus of Fig. 1.

Referring to Fig. 3, the apparatus of this figure shows an alternative arrangement similar to that shown in Fig. 2 for steam road territory, but dispensing with the checking transformer and its associated checking relay. It will be understood that the insulated rail joints A and B of Fig. 3 are constructed in the same manner as shown in Fig. 1 but the connections to these joints are somewhat different. The apparatus is so arranged that the rail joints A and B are checked

both as to insulation failure as well as breakage of the connections. The track transformer T2 has a mid-tap in its output winding, as in Fig. 2, but instead of a single track relay, two relays TR2a and TR2b are employed, of which relay TR2a is intended to perform the usual signal control functions. The apparatus operates as follows:

When the rail joints A and B are both intact, track circuit current from the track transformer T2 associated with relays TR2a and TR2b will flow over a circuit which may be traced from the upper rail 1, through wire 15, winding 16 of the auxiliary transformer ATa, wire 17, angle bar 2a, wire 18, angle bar 2, wires 19 and 20, angle bar 2a, wire 21, angle bar 2, wire 22, winding 23 of the auxiliary transformer ATb, and wire 24, to the lower rail 1a. Accordingly, both transformers ATa and ATb will be energized so that relays TR2a and TR2b will also be energized through the associated rectifiers Ra and Rb. The auxiliary track relay TR2b controls the energization of the main track relay TR2a over its front contact 25 and an obvious circuit.

If the insulation should break down at the right-hand half of the rail joint A between the rail 1 and either angle bar 2 or 2a, then winding 16 of the transformer ATa will be short-circuited so that relay TR2a will release. A breakdown of the insulation at the right-hand half of rail joint B, between the rail 1a and either angle bar 2 or 2a will similarly cause winding 23 of the transformer ATb to become short-circuited, thus releasing relay TR2b and causing relay TR2a to release, in turn, due to the opening of the front contact 25. Should the insulation break down between the rail 1 and either angle bar at the left-hand half of the rail joint A, then portion 26 of the output winding of the track transformer will be short-circuited so that the track circuit to the left of the faulty rail joint will be substantially deenergized. Likewise, a failure in the insulation between the rail 1a and either angle bar at the left-hand half of the rail joint B will place a short-circuit on portion 27 of the track transformer winding, again deenergizing the track circuit to the left of the rail joint.

It will be clear, therefore, that the apparatus of Fig. 3 provides practically complete protection against any failure at the rail joint. The only connection which is not automatically checked in Fig. 3 is the wire 28 which can, of course, be so arranged and connected as to make mechanical breakage thereof very unlikely and render visual inspection of the connection comparatively easy.

In Fig. 4, I have shown a modification of the apparatus of Fig. 3 in which the two track relays are replaced by a single track relay TR2 controlled from a single auxiliary transformer AT through a rectifier R. The energizing circuit for windings 16 and 23 of the transformer AT is identical with that traced for the corresponding windings in Fig. 3. The windings 16 and 23 are so connected as to aid one another in energizing the rectifier R and relay TR2. Should a failure develop at the right-hand half of either rail joint A or B, the associated winding 16 or 23 will be short-circuited, so that relay TR2 will release. Similarly, a failure at the left-hand half of either rail joint will short-circuit the respective portion 26 or 27 of the track transformer winding. The protection provided by the apparatus of either of Figs. 3 or 4 is, accordingly, substantially the same.

The apparatus described in the foregoing figures is not intended to provide protection against a failure involving a breakdown of the insulation at an end post such as 4 in Fig. 1. In actual practice, it has been found that a failure of an insulated rail joint over its end post is quite uncommon. It should also be noted that when the ordinary type of insulated rail joint protection is used, two failures must ordinarily occur before a connection is established between the adjoining rails and the protective apparatus is brought into play. That is, the insulation must fail between one angle bar and a rail and also between the same angle bar and the other rail. In the apparatus embodying my invention, however, a single failure of the insulation between an angle bar and a rail constitutes a broken-down rail joint and is detected by the apparatus. The result may be to accelerate the replacement of defective rail joints, but this will ordinarily be compensated for by an earlier discovery of a defect in the joint and an increase in the safety factor. As a rule, it has been found that when one portion of the rail joint breaks down, the remaining portions are about ready to give way also, so that prompt detection of the first failure is desirable.

Although I have herein shown and described only a few forms of track circuit apparatus embodying my invention, it is understood that various changes and modifications may be made therein within the scope of the appended claims without departing from the spirit and scope of my invention.

Having thus described my invention, what I claim is:

1. In combination, a stretch of railway track divided into adjoining track sections by means of an insulated rail joint in each rail of said track, each said insulated rail joint comprising a conducting bar on each side of the rail separated therefrom by insulation, a track transformer for one of said sections having a mid-tap in its track-connected winding, a first and a second detection relay for an adjoining track section, means for energizing said two detection relays from the rails of said adjoining section over a circuit which includes said conducting bars and the input windings of two transformers, one for each relay, all connected in series, and a connection from said mid-tap to said conducting bars, whereby a breakdown of the insulation between a conducting bar and a rail of said one section will short-circuit one half of said track transformer winding and whereby a breakdown of the insulation between a conducting bar and a rail of said adjoining section will short-circuit one of said input windings to thereby cause the associated detection relay to release.

2. In combination, a stretch of railway track divided into adjoining track sections by means of an insulated rail joint in each rail of said track, each said insulated rail joint comprising a conducting bar on each side of the rail separated therefrom by insulation, means for electrically connecting said conducting bars with one another, a track transformer connected across the rails of one of said sections for energizing the usual track circuit apparatus and having a mid-tap in its track-connected winding, and an electrical connection from said mid-tap to said conducting bars, whereby a breakdown of the insulation between a conducting bar and a rail of said one section will short-circuit one-half of said track transformer winding to thereby cause

substantial deenergization of said track circuit apparatus.

3. In combination, a stretch of railway track divided into adjoining track sections by means of an insulated rail joint in each rail of said track, each said insulated rail joint comprising a conducting bar on each side of the rail separated therefrom by insulation, a detection relay for each of said rail joints, means for energizing one of said detection relays from the rails of one of said sections over a circuit which includes said conducting bars in series, and means including a contact of said one detection relay for also energizing the other detection relay from the rails of said one section over said circuit, whereby a defect in said circuit will cause both of said relays to release.

4. In combination, a stretch of railway track divided into adjoining track sections by means of an insulated rail joint in each rail of said track, each said insulated rail joint comprising a conducting bar on each side of the rail separated therefrom by insulation, means for electrically connecting said conducting bars with one another in series, and a detection relay energized from across the rails of one of said sections over a circuit which includes said conducting bars and the electrical connections therebetween as well as the input winding of a transformer all in series, said input winding comprising two aiding portions, one terminal of each of said portions being connected respectively with one and the other rail of said one section, and the remaining terminal of each of said portions being connected respectively with the first and fourth of said conducting bars in said series arrangement thereof.

5. In combination, a stretch of railway track divided into adjoining track sections by means of an insulated rail joint in each rail of said track, each said insulated rail joint comprising a conducting bar on each side of the rail separated therefrom by insulation, means for electrically connecting said conducting bars with one another, a track transformer for one of said sections having a mid-tap in its track-connected winding, an electrical connection between said mid-tap and said conducting bars, and a detection relay energized from across the rails of an adjoining section over a circuit which in-

cludes said conducting bars and the electrical connections therebetween as well as the input winding of a transformer all in series, said input winding comprising two aiding portions, one terminal of each of said portions being connected respectively with one and the other rail of said adjoining section, and the remaining terminal of each of said portions being connected respectively with the first and fourth of said conducting bars in said series arrangement thereof.

6. In combination, a stretch of railway track divided into adjoining track sections by means of an insulated rail joint in each rail of said track, each said insulated rail joint comprising a conducting bar on each side of the rail separated therefrom by insulation, means for electrically connecting said conducting bars with one another in series, a track transformer for one of said sections having a mid-tap in its track-connected winding, a track relay for an adjoining section energized by a transformer having a track-connected input winding comprising two aiding portions, an electrical connection between said mid-tap and said conducting bars, and means for connecting the remaining terminals of said portions of the transformer input winding respectively with the first and fourth of said conducting bars in said series arrangement thereof.

7. In combination, a stretch of railway track divided into adjoining track sections by means of an insulated rail joint in each rail of said track, each said insulated rail joint comprising a conducting bar on each side of the rail separated therefrom by insulation, a detection relay for each of said rail joints, and means for energizing said two detection relays from the rails of one of said sections over a circuit which includes said conducting bars and the input windings of two transformers, one for each relay, all connected in series, whereby a breakdown of the insulation between a conducting bar and a rail of said one section will cause the input winding of one of said transformers to become short-circuited to thereby release the associated detection relay and whereby a defect in said circuit will cause both detection relays to release.
